CLAIM

The ornamental design for a monitor cover, as shown and described.

DESCRIPTION

FIG. 1 is a front perspective view of a monitor cover;
 FIG. 2 is a back perspective view thereof;
 FIG. 3 is a front elevation view thereof;
 FIG. 4 is a back elevation view thereof;
 FIG. 5 is a right side elevation view thereof;
 FIG. 6 is a left side elevation view thereof;
 FIG. 7 is a top plan view thereof;
 FIG. 8 is a bottom plan view thereof; and,
 FIG. 9 is a front perspective view thereof shown in an environment of use.

The monitor depicted by broken lines in FIG. 9 is shown for the purpose of illustrating an environmental feature that forms no part of the claimed design.
